US0D1000817S

(12) United States Design Patent (10) Patent No.: US D1,000,817 S
(45) Date of Patent: * Oct. 10, 2023

(54) SHOE

(71) Applicant: NIKE, Inc., Beaverton, OR (US)

(72) Inventor: John Paul Managa, Portland, OR (US)

(73) Assignee: NIKE, Inc., Beaverton, OR (US)

() Term: 15 Years

(21) Appl. No.: 29/819,927

(22) Filed: Dec. 17, 2021

(51) LOC (14) Cl. 02-04

(52) U.S. Cl.

USPC D2/972

(58) Field of Classification Search

USPC D2/946, 947, 969, 972, 973, 977, 978

CLAIM

The ornamental design for a shoe, as shown and described.

DESCRIPTION

FIG. 1 is a side view thereof;

FIG. 2 is a rear perspective view thereof;

FIG. 3 is a rear view thereof;

FIG. 4 is an opposite side rear perspective view thereof; and, FIG. 5 is an opposite side view thereof.

The broken line showing of the unshaded regions within the photographic area form no part of the claimed design. The broken lines depicting the remainder of the shoe form no part of the claimed design.

1 Claim, 5 Drawing Sheets
